UNITED STATES PATENT OFFICE.

WILLIAM BERRY HOLLAND, OF SYDNEY, NEW SOUTH WALES, AUSTRALIA.

HAND LOADER FOR CONCRETE MIXERS.

Application filed July 31, 1925, Serial No. 47,382, and in Australia August 16, 1924.

This invention relates to concrete batch mixers of the tilting drum type. In these machines the drum is tipped over angularly to one side of the frame for loading purposes and the concrete ingredients are shoveled into it or elevated into it. When the drum is thus charged it is swung to the erect position and it is rotated to effect intermixture of the ingredients and finally it is tipped over to the opposite side to spill out the mixed batch of concrete.

The present invention consists in an improved type of loader which is applicable or adaptable to drum mixers which are so mounted that they may be tilted transversely on the carriage or frame on which they are mounted. The loader in which the present invention consists is characterized in that a scoop shape hopper is supported on a pivotally mounted bracket frame and counterbalanced by springs or by weights, the tension of which is so adjusted that they overbalance the weight of the hopper when empty. These counterbalances operate to assist the lifting of the hopper to the upper or discharging position, the overplus of counterbalance is insufficient for preventing the easy restoration of the hopper by manual pull downward applied to a hand bail fitted to the back of the hopper but offering material assistance to the manual operator in the upraising of the hopper to discharge its contents into the drum. The counterbalance is preferably obtained by means of springs having adjustable tensioning devices associated with them whereby the most suitable degree of counterbalance to facilitate the work of the laborer who is called upon to draw the hopper down and to upraise it is minimized. The hopper being lowered to the frame whilst the drum is in rotation effecting the mixing, the filling of the hopper for the next mix can be proceeded with simultaneously with the operation of mixing. The hopper being of scoop shape, when mounted so that in the filling position it is tipped backward, serves as a convenient gauge for the volume of the charge to be introduced at each filling of the drum.

In the accompanying drawings:—

Fig. 1 is a perspective elevational view of the loader fitted to a concrete mixer of the conventional drum type, the hopper being shown in the down-set refilling position ready to receive the ingredients to be

mixed, and the drum being shown tipped towards the hopper to receive the charge from the hopper when the hopper is raised to its discharging position; and,

Fig. 2 is a similar view showing the hopper in the tipped position in which its gauged contents of concrete making ingredients are in process of being discharged into the mixing drum; portion of the lower part of this figure is omitted.

The drum 10 is mounted on trunnions 11 and is fitted with the usual ring gear 12 with which a driving pinion intermeshes. The trunnion spindle 13 has fixed upon it the canting levers 14 and 15. By means of these levers the operators swing the drum to filling side or discharging side position or to the mid position in which the mixing is effected. The locking of the drum in either of these three positions is effected by the engagement of the levers 14—15 which are slideable on the spindle 13 though keyed to it, with the cross slotted check lock face 16 which is fixed on the support bracket 17, 18 being a helical spring in compression which tends to slide the eyes of the levers 14 and 15 along the spindle 13 and enter them in one or other of the cross slots in the face 16.

At the distant end of the frame, a motor is mounted for applying rotational movement to the drum 10, but in some cases the rotation of the drum is effected from an engine otherwise mounted through a chain and a sprocket on the shaft which carries the pinion which intermeshes with the ring gear 12. The whole of this equipment is mounted on a frame 19 carried on wheeled axles 20 and 21. The whole construction thus far described is well known in the art.

Fixed transversely to the frame 19 are two brackets 22 and 23 connected together at the outer end by a transom piece 24 and having at their outer ends two lugs which may be downbent from the frames. These lugs 25 are apertured to carry the tail rods 26 to which the forward ends of the counterbalance springs 27 are anchored. The tension of the springs 27 is adjustable by moving the back nut 28 and the set nut 29 on the respective tail rods. 30 is a pawl latch mounted on a lug bracket 31 depending from the bent frame members 22, 23, 32 being a fixed abutment piece and 33 a cushion spring disposed between the abutment piece 32 and the pawl 30. 34 is a forward stop to limit

the outward movement of the pawl 30. 35 is a prop leg pivotally carried at 36 on the transom member 24 and bent at its foot end or flanged or otherwise formed to take 5 spread bearing on the ground and support the overhang of the frame 22-23 and the load superposed on it. The prop 35 may be inswung and hung up under the frame temporarily whilst the apparatus is being 10 wheeled from place to place.

The horizontally disposed portions of the bent frame brackets 22-23 are located near the mouth level of the drum 10 when the drum is tilted to the filling position as seen 15 in the drawings. The measuring and filling hopper 40 is carried on a frame constituted of underneath strut members 41 and forward support members 42 both mounted on an axle 43 the ends of which are carried in 20 the frame members 22-23. The forward support members 42 are extended below the axle 43 to form counterbalance anchor arms 44. The inner ends of the springs 27 are hooked into or otherwise attached to these 25 arms 44. At the rear end of it the hopper 40 is fitted with a hand bail 50. The arms 51 of this bail are cranked at right angles or approximately so, the crank portion of 30 one arm being down set and terminated at its bottom end in a hook or catch 52 which is engageable with the pawl 30. The arms 51 are pivotally mounted on the hopper sides at 53 and one of them passes through a 35 guide slot 54 formed on the hopper side, the length of this slot being such as to permit the necessary freedom of motion to the hook or catch 52 to enable its engagement with and its disengagement from the pawl 30.

40 It is quite practicable to substitute a weight or weights for the springs 27 to counterbalance the hopper 40. So long as the hopper is mounted to move about a centre such as the axle 43 located under the 45 forward portion of it the weights may be arranged to operate through any intermediate lever or tackle mechanism to assist in the uplifting of the hopper and to resist more or less the return of the empty hopper 50 from the tipping position shown in Fig. 2 to the refilling position shown in Fig. 1. Owing to the location of the pivot centre at the axle 43 being below the forward end of the hopper 40, the hopper is tipped backward as seen in Fig. 1 when it is brought to the refilling position. As the tension of the spring 27 or the pull of any equivalent counterbalancing device suffices to hold the hopper in the normally upward tipped position shown in Fig. 2, it is necessary for the laborer to exercise some degree of force to pull it out and downwards to bring it to the charging position. As this resetting is effected by down pull and the overbalance 55 is appropriately regulated by the spring

tension or the counterweight loading, the return of the hopper from the Fig. 1 to the Fig. 2 position is readily effected by a laborer in a down pull movement, the movement being continued until the catch 52 70 latches into the pawl 30. In the filling position, the hopper being canted backwards as seen in Fig. 1 so that its back top edge sets about horizontally with its mouth, the hopper forms a convenient gauging device for 75 the volume of charge, the laborers shovelling the ingredients into it until the charge is brought up to horizontal level between the lip and top back edge of it. The drum having been discharged by tipping it over to 80 the left, is swung over its centre and tipped to the right so that its mouth faces the hopper. A laborer then forcing the bail 50 upward, releases the hook or catch 52 from the pawl 30, and assisted by the counterweight 85 action pushes the hopper upward from the Fig. 1 to the Fig. 2 position with great facility. The angular position of the hopper as at Fig. 2 being steeper than the resting angle of the concrete ingredients, 90 the gauged charge in the hopper slides immediately therefrom into the drum 10. The drum is then immediately reversed over to the mixing position, the hopper 40 being meanwhile brought back to the 95 Fig. 1 position and refilled whilst the mixing proceeds in the drum. When the mixing has been effected the drum 10 is tipped to the left-hand position to discharge the mix, and is then, as before, immediately 100 swung over to the right hand position seen in Fig. 1, by which time another charge is ready in the hopper 40 and is immediately delivered therefrom into the drum 10.

What I claim as my invention and desire 105 to secure by Letters Patent is:—

1. A hand operated loading attachment for rotary drum concrete batch mixers, including a charging hopper and counterbalancing springs adapted to swing the loaded hopper upward into the discharging position and to normally retain the empty hopper in that position.

2. A hand loader attachment according to 115 claim 1 characterized in that the counterbalance is adjustable and is normally proportioned to overbalance the empty hopper and thereby necessitate the application of a downwardly directed force to re-set the hopper in the refilling position.

3. A hand operated loading attachment 125 for drum type concrete batch mixers, comprising a frame partly supported on the mixer frame, and having a horizontally disposed portion about the level of the mixer mouth; a scoop type hopper mounted for tipping on an axle on said frame near the mixer drum mouth and below the open front end of the hopper; means for counterbalancing the hopper, and a bail at the outer 130

end of the hopper having a catch hook adapted to engage a pawl on the frame to hold the hopper in downset position resting on the frame against the pull of the counterbalance.

4. A hand loader attachment for drum type concrete batch mixers, comprising frame members extended laterally from the mixer frame, and having a prop support for the outboard end, a cradle pivotally mounted in said frame adjacent the drum, a scoop shaped hopper supported on said cradle above its pivot centre, said centre located under the forward part of said hop-

per, extension arms on the cradle, counterbalanced springs connected at one end of them to said arms and at the other end of them to tension adjusting devices, a latch bail at the back end of the hopper, and members on the frame engageable by said bail latch adapted for holding the hopper down against the counterweight pull whilst it is in the refilling position, substantially as described.

In testimony whereof I have signed my name to this specification.

WILLIAM BERRY HOLLAND.
